UNITED STATES PATENT OFFICE.

CHRISTIAN V. LUCIUS, OF MASSILLON, OHIO.

METALLIC GRAVE-VAULT.

1,359,402.

Specification of Letters Patent. Patented Nov. 16, 1920.

Application filed March 13, 1919. Serial No. 282,411.

To all whom it may concern:

Be it known that I, CHRISTIAN V. LUCIUS, a citizen of the United States, residing at Massillon, in the county of Stark and State 5 of Ohio, have invented certain new and useful Improvements in Metallic Grave-Vaults, of which the following is a specification.

My invention relates to improvements in metallic grave vaults, and more particularly 10 to that class or type which are adapted to receive and hermetically seal the casket and protect the latter from grave robbers as well as from deteriorating elements.

The primary object of the invention is to 15 provide a generally improved metallic vault of this class, which will be exceedingly simple in construction, cheap of manufacture, and efficient in use.

A further object is the provision of a 20 metallic vault provided with an improved removable head or door, together with improved means for clamping, sealing and securing the same after the casket has been inserted in the vault.

25 A still further and very important object of the invention is the provision of a grave vault made entirely of sheet metal particularly designed and adapted to be welded throughout through the agency of "auto-geneous" welding, or other welding processes, thereby eliminating the use of rivets or other fastening elements, the edges of the metal parts being particularly arranged and disposed to present welding edges adapted 35 to such welding processes.

With the above mentioned and other ends in view, the invention consists in the novel construction, arrangement, and combination of parts, hereinafter described, illustrated in 40 one of its embodiments in the accompanying drawings, and particularly pointed out in the appended claim.

Referring to the drawings, forming a part of this specification, Figure 1, is a perspective view of the improved metallic vault with the removable head or door removed.

Fig. 2, a transverse or cross sectional view of the same.

Fig. 3, a view of the inner side of the 50 removable head or door, removed.

Fig. 4, a fragmentary longitudinal sectional view of the improved vault, illustrating in particular the manner of securing the permanent and removable heads therein.

55 Fig. 5, a top plan view of the vault truck for receiving and supporting one end of the

casket as the latter is inserted into the vault from the open end thereof.

Fig. 6, an end view of the casket receiving and supporting truck.

Similar numerals of reference designate like parts throughout all the figures of the drawings.

The improved vault body is made up of a single blank or sheet of metal bent and 65 folded longitudinally of its length to form the top and side walls 1 and 2, respectively, and having its free or meeting end portions arranged beneath to form the bottom wall 3, the ends of said blank of sheet metal abut- 70ting against each other and extending longitudinally of the bottom of the vault body forming abutting edges united by means of a longitudinally extending line of welding 3^a, as shown most clearly in Fig. 2 of the 75 drawings.

As a means of forming a suitable rail or track-way for receiving and supporting a suitable casket receiving and supporting truck hereinafter described, the bottom wall 80 3, of the vault body is provided with a pair of spaced rails 4, the base flanges thereof being secured and welded to the bottom wall 3, as for example by means of a line of welding 4^a, along the edges of the flanges of the 85 rails. It will also be observed that one of the rails 4, is arranged immediately above the welded edges of the sheet of metal forming the vault body and united by the welding 3^a, and it will also be observed that such 90 rail so welded will act to further secure and reinforce such adjacent and abutting edges of the blank of sheet metal.

The improved vault body is provided with a permanent or fixed head 5, having inwardly extending welding flanges 5^a, as shown most clearly in Fig. 4 of the drawings.

The opposite end of the vault body is provided with a removable head or door 6, 100 adapted to open and close the open end of the vault body for the purpose of inserting the casket and thereafter fastening and sealing said removable head after which the vault may be lowered into the grave through 105 the medium of the handles 7, and any suitable and convenient casket or vault lowering device.

As a means of securing the removable head or door 6, in position, and particularly as a means of automatically locking and sealing the same, the ends of the me-

metallic vault body are provided with a head supporting and sealing member 8, and as a means of welding the latter to the edges of the metallic vault body, said sealing member 8, is provided with inwardly extending welding flanges 8^a, and as a means of securely clamping and sealing the removable head 6, in position, the head supporting and sealing member 8, is provided 10 with a series of suitable fastening members, said fastening members, in the present instance, comprising a plurality of fixed threaded bolt members 9, extending outwardly and adapted to pass through a series 15 of similarly spaced bolt receiving openings 6^a, in the marginal clamping and sealing flange 6^b, of the head 6.

As a further means of sealing the removable head 6, the outer or face side of 20 the head supporting and sealing member 8, is provided with a gasket 10, of any suitable and convenient material, and the threaded bolts 9, are provided with wing nuts 9^a, for securely clamping the head 6, 25 upon the gasket 10.

As a means of automatically locking the removable head 6 in position when closed so that no one will be able to open the same, the inner side of the head 6, is provided 30 with a plurality of locks comprising suitable lock casings 11, provided with spring pressed lock or plunger members 11^a, having inclined portions 11^b, adapted, when the head 6, is pressed into position, to bear 35 against and to coöperate with the inner side of the head supporting and sealing member 8, and after passing the latter to

snap into engagement therewith in an obvious and well known manner, thereby securely locking the same in position, as 40 shown in Fig. 4 of the drawings.

As a convenient means of inserting the casket into the vault through the open end of the latter when the head 6 has been removed, the vault body is provided with a 45 removable truck, comprising a main or cross member 12, and truck or side carriage members 12^a, the latter being provided with grooved wheels 12^b, adapted to travel upon the rails 4, of the track-way. The truck 50 cross member 12, is provided with a pair of casket engaging and supporting pins 12^c, adapted to engage with the under side of the casket at one end thereof as the casket is inserted and passed into the metallic 55 vault.

From the foregoing description, taken in connection with the accompanying drawings, the operation and advantages of my invention will be readily understood. 60

Having thus described one of the embodiments of my invention, what I claim and desire to secure by Letters Patent, is,—

In a vault, a metallic vault body made up of a blank of sheet metal folded longitudinally and having its edges abutting and welded along its bottom portion, and rails welded on said bottom, one of said rails being welded above and to the abutting edges of said vault body. 65 70

In testimony whereof I have affixed my signature.

CHRISTIAN V. LUCIUS.
